GLADYS L. KIRKPATRICK, OF GREENSBURG, INDIANA, ASSIGNOR OF ONE-HALF TO
JOHN E. ROBBINS, OF GREENSBURG, INDIANA.

BOY'S PANTS.

1,353,480.

Specification of Letters Patent. Patented Sept. 21, 1920.

Application filed March 19, 1920. Serial No. 367,172.

To all whom it may concern:

Be it known that I, GLADYS L. KIRKPATRICK, a citizen of the United States, residing at Greensburg, in the county of Decatur and

5 State of Indiana, have invented a new and useful Boy's Pants, of which the following is a specification.

It is the object of my invention to provide the opening in the front of boys' pants 10 with an effective closing device which while not interfering with the utility of the opening will not by carelessness on the part of the boy be liable to protrude therethrough in the way ordinary closing flaps do.

15 The accompanying drawings illustrate my invention: Figure 1 is a rear view of a pair of boys' pants, with the hinder part let down to show my closing device for the front opening; and Fig. 2 is an enlarged fragmentary rear view of the closing device and the part of the pants around such opening.

The boys' pants 10 have the usual front opening 11, usually provided in a front medial seam 12. Behind the opening 11, 25 on the inside of the pants, I place a piece of fabric 13, usually of the same material as the pants. This piece 13 is larger than the opening 11; and it is conveniently an equilateral rectangle, square or diamond-shaped, set cornerwise. It projects laterally on both sides of the seam 12, and both above and below the opening 11 it is stitched to the pants by cross-stitching 14 which crosses such seam and extends some distance therefrom in both directions, preferably to the edge of the closing piece 13. The piece 13 is free between the two rows of cross-stitching 14, on both sides, so that either side corner thereof may be pushed aside in order to 40 give access to the opening 11 when that is necessary. It is found that in use these side corners will rarely if ever protrude through

the opening 11, no matter how careless the boy may be, and that when the opening is not in use it is always fully covered by the 45 piece 13.

I claim as my invention:

1. In boys' pants, the combination with the pants having the usual front opening, of a separate closing piece of fabric located 50 behind such opening and stitched to the pants body above and below the opening only and unattached between such stitches.

2. In boys' pants, the combination with the pants having the usual front opening, of 55 a separate closing piece of fabric located behind such opening and stitched to the pants body above and below the opening only and unattached between such stitches, said stitching projecting laterally on both sides 60 beyond the vertical line of such opening.

3. In boys' pants, the combination with the pants having the usual front opening, of a separate closing piece of fabric located 65 behind such opening and stitched to the pants body above and below the opening only and unattached between such stitches, said closing piece being a substantially equilateral rectangle set cornerwise.

4. In boys' pants, the combination with 70 the pants having the usual front opening, of a closing piece of fabric located behind such opening to cover it, said closing piece being free at a side to give access to the opening but being fastened to the pants above and 75 below such opening at points offset toward such free side from the vertical line of such opening.

In witness whereof I, GLADYS L. KIRKPATRICK, have hereunto set my hand at Greensburg, Indiana, this 29th day of January, 80 A. D. one thousand nine hundred and twenty.

GLADYS L. KIRKPATRICK.
